UNITED STATES PATENT OFFICE

149,030

DESIGN FOR A TRENCHING MACHINE
FRAME

George A. Vaughn, Newton, Iowa

Application November 21, 1946, Serial No. 134,986

Term of patent 14 years

(Cl. D14—3)

To all whom it may concern:

Be it known that I, George A. Vaughn, a citizen of the United States, residing at Newton, in the county of Jasper and State of Iowa, have invented a new, original, and ornamental Design for a Trenching Machine Frame, of which the following is a specification, reference being had to the accompanying drawing, forming a part thereof, wherein:

Figure 1 is a side elevational view of a trenching machine frame embodying the design of my invention.

Figure 2 is a view similar to Figure 1, showing the opposite side of the trenching machine frame.

Figure 3 is a top plan view of said trenching machine frame.

Figure 4 is a rear end elevational view.

Figure 5 is a front end elevational view.

This application is a continuation in part of my copending application Ser. #D. 120,469 filed July 3, 1945.

I claim:

The ornamental design for a trenching machine frame, substantially as shown.

GEORGE A. VAUGHN.
